ASSIGNEES TO FLANNERY BOLT COMPANY, OF PITTSBURGH, PENNSYLVANIA.

STAY-BOLT FOR BOILERS

1,236,015.

Specification of Letters Patent. Patented Aug. 7, 1917.

Application filed November 24, 1914. Serial No. 873,784.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Stay-Bolts for Boilers; and we do hereby declare the following to be a full, clear, and exact description of the invention, such as will enable others skilled in the art to which it appertains to make and use the same.

Our invention relates to an improvement in stay bolts for boilers, the object being to provide a yielding coupling for one end of the bolt, whereby the latter will be flexibly supported so that it may be free to follow the movements of the fire box sheet of the boiler without unduly straining either of the sheets.

With this object in view our invention consists in a sleeve composed of two detachably connected members the outer one of which is constructed to yield or give and thus permit the stay bolt, the head of which is in contact with same, to accommodate itself to the movements of the boiler sheets without unduly straining either of the sheets.

In the accompanying drawings, Figure 1 is a view in elevation of a coupling sleeve embodying our invention; Fig. 2 is a view in section through same and also showing the bolt in place and Figs. 3, 4, 5, 5^a, 6, 7, 8, 9, 10, 11 and 12 are views in longitudinal section of modified forms.

1 represents a bushing threaded externally for its attachment to the outer sheet of a boiler, and provided internally with a rounded seat for the head 3 of the stay bolt 4, the latter adapted to be secured at its other end to the inner sheet of the boiler. The bushing 1 is made flaring from the seat 2 to its inner end, so as to permit the bolt to have the necessary rocking movement on its seat in the bushing. Secured to the outer threaded end of the bushing 1 is the cap 5 which is preferably made of spring metal or stay bolt metal heat treated and cooled in oil so as to render it yielding. This cap is provided with one or more convolutions, folds or flutes 6, so located as to permit the central portion thereof, which bears against the head of the bolt, to yield or give under a

longitudinal pressure or stress applied to the bolt. In the construction shown in Fig. 1 and 2 the central portion of the cap 5 is projected inwardly in the form of a nipple 7, the free end of which is curved concentric with the curved bearing 2, in bushing 1, and rests against a concave seat 8 formed in the bolt head 3. The curved seat 8 is also concentric with the curved seat 2, so that when the parts are assembled, the head of the bolt is free to turn in any direction on its seat 2. The nipple 7 yieldingly holds the bolt 4 onto its seat 2, but the spring formation of the cap permits the nipple 7 to be moved outwardly under any longitudinal stresses that may be imparted to the bolt 4, thus permitting the bolt to respond to the movement of the fire box sheet of the boiler without unduly straining either of the sheets. We have also shown the nipple 7 with a central bore 9, which communicates with the tell-tale 10 formed in the bolt, so that in the event the bolt should be fractured at the juncture of the neck and head, which is the point where fracture nearly universally occurs, the steam or water may issue through the bore 9 and indicate the existence of a fracture in the bolt.

In Fig. 3 we have shown the cap 5^a with a plurality of folds 6^a, the central part of the cap being turned inwardly as at 11 to form the nipple, and flared downwardly so as to rest on the convex seat 12 formed on the outer end of the bolt, the convex seat 12 being concentric with the seat 2 so as to permit the bolt head 3^a to turn freely on its seat.

The construction shown in Fig. 4 is substantially identical with that shown in Fig. 3, except that the bolt head 3^b has a concave seat to receive the inwardly turned central nipple 13 of the cap 5^b, the curvature of the seat in the bolt head being concentric with the seat 2 for the bolt head in the bushing 1.

In the construction shown in Figs. 5 and 5^a, the cap 5^a is composed of two members 5^a and 5^b, united around the central axis of the cap, the free edge of the inner member terminating adjacent the outer end of the bushing and bearing against the head 3 of the bolt, in advance, or outside of the greatest diameter of the latter. If desired the free edge of the inner member may bear against a shoulder on the head of the bolt, as shown in Fig. 5, or the head may be of

an unbroken curvature as shown in Fig. 5^a. In either event the free edge of the inner member bears on the head of the bolt with a yielding pressure, and is free to give or 5 yield so as to permit the bolt to move or expand longitudinally, but maintaining at all times a steam tight joint which prevents leakage even when the bolt head is off its seat 2.

10 In Fig. 6 the cap 5^a is formed of a series of folds within the outer member, the several folds being substantially parallel and terminating centrally in an inwardly projecting hollow nipple 7^a, the free end of 15 which is rounded and rests on a concave seat 7^b, at the bottom of the recess within the head, the curvature of the seat 7^b and the rounded end 7^c of the nipple 7^a, being concentric with the curved seat 2 in the socket 1.

20 In the construction shown in Fig. 7, the folds extend circumferentially around the cap substantially in planes at right angles to the long axis of the bolt, and the cap is provided centrally with a hollow nipple integral with the top fold, and terminating in 25 a curved head 9^a which rests within a concave seat 9^b at the center of the head of the bolt, the said head 9^a and seat 9^b being concentric with the seat 2 in bushing 1. The 30 construction disclosed in Fig. 8 is substantially identical with that shown in Fig. 7, except that the nipple 9^a is separate from the cap and is secured thereto by screw threads.

35 In Fig. 9 the cap 5^b is provided with folds formed in the cap substantially at right angles to the long axis of the bolt, one end of said folds 11 forming a seat for the head of the bolt, the bearing face of the fold 40 being curved to conform to the curvature of the head. The outer end of the cap has a central bore which is internally threaded and closed by a plug 12, which may have a tell-tale bore 13 for the escape of steam 45 or water.

In Fig. 10 the folds or convolutions in the cap 5^c are diagonally disposed to the long axis of the bolt, and the latter is provided centrally with a threaded opening for the nipple 14, the lower end of which is rounded and rests on a concave seat within 50 a recess in the head of the bolt as previously described. The construction shown in Fig. 11 is identical with that shown in Fig. 10, except that the nipple 14 is made independent of the plug 15 and has a semispherical bearing against the plug and also against the head of the bolt.

55 In the construction shown in Fig. 12, the sleeve or bushing 16 projects considerably above the seat 2 for the head of the bolt, and is internally threaded at its outer end to receive the cap 5^m. The outer end of this cap is made heavy and threaded externally, 60 and the lower or inner part is hollow and

convoluted or fluted or folded so that it may give or yield under longitudinal stresses to which the bolt is subjected, the extreme inner end of the cap being concaved to make a close and steam tight fit with the head 70 of the bolt.

In each construction above described, the cap of the bushing yieldingly sustains the bolt against longitudinal movement and returns it to its seat within the bushing as 75 soon as the longitudinal stress is relieved, and when so supporting the bolt, forms a steam tight joint with the head of the latter so as to prevent the escape of steam or water. The bolt therefore is free to have a 80 universal rocking movement in the bushing, and is also free to move longitudinally, so that it can respond to the movements of the fire box sheet, without buckling or unduly straining either of the sheets.

85 It is evident that many slight changes might be resorted to in the relative arrangement of parts shown and described without departing from the spirit and scope of our invention. Hence we would have it understood that we do not wish to confine ourselves to the exact construction and arrangement of parts shown and described, except as required by the scope of the appended claims.

90 Having fully described our invention what we claim as new and desire to secure by Letters Patent, is:—

1. A device of the character described comprising a bolt having an opening formed 100 therein, a sleeve having an opening through which said bolt passes, a cap on said sleeve, said cap being provided with an opening, and a fillet arranged between said cap and said bolt, said fillet being provided with an 105 opening communicating with the openings in the bolt and cap.

2. The combination with the inner and outer sheets of a boiler, of a sleeve threaded into an opening in one of the sheets, said sleeve being provided with an opening and an enlarged recess, a bolt extending through said opening having threaded engagement with the other sheet of said boiler, an enlargement formed on said bolt for engagement with the recess of the sleeve, said bolt being provided with a bore, a recess formed in said bolt communicating with said bore, a cap on said sleeve, and a fillet arranged 110 between said cap and said bolt, the fillet being provided with a curved end for engagement in the recess of the bolt, the cap being provided with an opening, and an opening formed in said fillet in communication with the opening in the bolt and cap. 115

3. A stay bolt comprising a body having an opening formed therein and an enlarged end, a sleeve engaged around said stay bolt and having a recess for accommodating said enlarged end, a cap on said sleeve, and a 120

130

fillet arranged between said cap and said enlarged end of the said bolt, said fillet serving to space said cap from said stay bolt.

4. In stay bolts for boilers, the combination of a bushing adapted for attachment to the outer sheet of a boiler, a stay bolt the head of which is seated in said bushing, and a yielding or resilient cap detachably secured to said bushing and bearing against

10 the head of the bolt.

5. In stay bolts for boilers, the combination of a bushing adapted for attachment to the outer sheet of a boiler and provided internally with a curved seat, a stay bolt having a curved head resting on said curved seat, and a yielding or resilient cap detachably secured to said bushing and forming a yielding abutment for the bolt.

6. A bushing for boiler stay bolts having an internal seat for the head of the bolt, and a yielding cap detachably secured to said bushing and forming a yielding abutment against which the head of the stay bolt bears.

25 7. In stay bolts for boilers, the combination of a bushing having an internal seat for the head of a stay bolt, a stay bolt having a head adapted to rest on said seat, and a cap secured to the bushing and having a bearing 30 for the head of the bolt, the portion of the cap intermediate its attachment to the bushing and its part which bears on the head of the bolt being yielding so as to permit it to give under endwise pressure on the bolt.

8. In stay bolts for boilers, the combination of a bushing having an internal seat for the head of a stay bolt, a stay bolt having a head adapted to rest on said seat, and a cap secured to the bushing and having a bearing 40 against which the head of the bolt rests, the said cap being fluted or convoluted between

its attachment to the bushing and its bearing for the head of the bolt, whereby it is free to yield or give under endwise pressure of the bolt.

45

9. In stay bolts for boilers, the combination of a bushing having an internal seat for the head of a bolt, a bolt having a head resting on said seat, and a cap secured to the bushing and having an inwardly projecting 50 end bearing against the head of the bolt and forming an abutment for the same, the portion of the cap intermediate its attachment to the bushing and its abutment for the bolt head being fluted or convoluted whereby it 55 will be free to yield or give under endwise pressure on the bolt.

10. In stay bolts for boilers, the combination of a bushing having an internal seat for the head of a bolt, a bolt having a head resting on said seat the said bolt head having a tell-tale bore and a cap secured to the bushing and bearing against the head, the said cap having an opening in alignment with the tell-tale bore in the bolt head and also 60 shaped intermediate said opening and secured end so that it can give or yield under longitudinal stresses imparted to the bolt.

11. In stay bolts for boilers, the combination of a stay bolt, a seat for the head of the 70 same and a yielding resilient cap secured to the part having the seat and bearing against the head of the bolt.

In testimony whereof, we have signed this specification in the presence of two subscribing witnesses.
